UNITED STATES PATENT OFFICE.

GEORGE A. WEBSTER, OF SANDWICH, ILLINOIS

HOT-WATER HEATER AND RADIATOR.

1,098,537.

Specification of Letters Patent.

Patented June 2, 1914.

Application filed January 26, 1914. Serial No. 814,400.

To all whom it may concern:

Be it known that I, GEORGE A. WEBSTER, a citizen of the United States, and resident of Sandwich, county of DeKalb, and State of Illinois, have invented certain new and useful Improvements in Hot-Water Heaters and Radiators, of which the following is a specification, and which are illustrated in the accompanying drawings, forming a part thereof.

The invention relates to heating appliances and more particularly to those designed for independently heating the individual rooms of a building or adjacent rooms of a suite or apartment.

To this end the invention contemplates a hot water heater adapted to serve both as a radiator and as a means for supplying heated water to one or more radiators.

The object of the invention is to provide heating apparatus which may be conveniently installed and which will be both economical and effective in operation.

In the accompanying drawings, Figure 1 is a detail sectional view drawn in perspective and illustrating an installation of heating apparatus embodying the features of improvement provided by the invention for supplying heat to adjacent rooms of a building; Fig. 2 is a central vertical transverse sectional view of the hot water heater and radiators which is included in the apparatus illustrated in Fig. 1; and Figs. 3 and 4 are detail central longitudinal sectional views showing the two end portions of the heater and Fig. 4 being drawn upon a larger scale than Fig. 3.

In carrying out the invention provision is made for completely surrounding a heating chamber with hollow walls which are so constructed as to confine the water to be heated in narrow columns having an extended surface and to prevent the escape of products of combustion from the heating chamber until substantially all of their heat has been absorbed. As shown, an oblong rectangular shell or casing 10 is provided. This casing is conveniently formed from cast iron and has a removable cover 11. Suitable legs, as 12, may be applied to the bottom of the shell for supporting the same in an upright position above the floor after the manner of supporting the cast iron radiators which are now in common use.

A second shell 13, preferably of the same shape as the shell 10 but of smaller dimen-

sions, is mounted within the chamber of the first mentioned shell. The shell 13 is conveniently formed from sheet metal. In constructing the same the top 14 will preferably be secured in place after certain parts to be hereinafter described have been mounted within its chamber, as 15. Most desirably the shell 13 is so supported within the chamber of the shell 10 that a narrow water space 16 extends entirely about the sides and ends and beneath the floor or bottom of the shell 13. A water space, as 17, of greater width than the water space 16, is provided between the top 14 of the shell 13 and the cover 11 of the shell 10. Openings, as 18 and 19, in the cover 11 provide respectively for the connection of a water supply pipe 20 and a relief valve 21. Openings, as 22 and 23 in one of the end walls of the shell 10 and preferably located at different levels, provide for the connection of circulating pipes, as 24, 25. These circulating pipes may lead to a radiator, as 26 which is located at a distance, as in a different room from the parts heretofore described, but preferably upon the same floor. The radiator 26 is of usual construction but when located upon the same floor with the heater, as shown it will desirably be of less height than the shell 10 to insure a sufficient head of water for the required circulation being maintained in the latter.

The heater is desirably supplied with gaseous fuel, as through a pipe 27. This pipe may be connected with a burner 28 located within the chamber 15 of the shell 13. To provide for the projection of the receiving end, as 29, of the burner through the walls of the shells 10 and 13, the shell 13 is provided with a nipple 30 which registers with and extends through an opening 31 in the adjacent end wall of the shell 10. A spacing ring 32 mounted on the nipple 30 inside of the shell 10 and a clamping nut 33 which runs on the outer end of the nipple 30 serve for clamping the parts together for making a water tight joint between the wall of the shell 10 and the nipple.

Nipples, as 34 and 35, each enter registering openings, as 36 and 37 in the side walls of the shells 10 and 13, respectively. A spacing ring 38 and clamping nut 39, similar respectively to the spacing ring 32 and the clamping nut 33, are provided upon each of the nipples 34 and 35 for making a water tight joint between the corresponding nipple

and the side walls of the shell 10 and 13. One of the nipples, as 34, serves for the introduction of a match to light the burner 28, as also for supplying air to the flame 5 and for permitting the examination of its condition. The other nipple, as 35, provides for the attachment of a ventilating flue, as 40, Fig. 2.

A substantially complete absorption of all 10 of the heat from the burner 28 is insured by the use of a plurality of chambered baffle plates, as 41, within the chamber 15 of the shell 13. Each of these baffle plates is preferably of crescent shape in cross section and 15 is horizontally extended from end to end of the chamber 15 with its concave surface facing downward. In order to insure engagement of the heated air and products of combustion from the burner 28 with all of the 20 baffle plates, each baffle plate is desirably of less width than the width of the chamber 15 and adjacent baffle plates are located at opposite sides of the chamber. A zig-zag course for the heated air and products of 25 combustion upwardly through the chamber 15 is thereby insured.

A circulation of the water to be heated through the chambers of the baffle plates is obtained by connecting them, at each end of 30 the baffle plates, with the water space 16 at the corresponding end of the heater. This is conveniently accomplished in the manner illustrated in Fig. 4. As shown, a threaded opening 42, is provided at each end of each 35 of the baffle plates, and there are openings 43 through the end walls of the shell 13 communicating therewith. A threaded nipple 44 having a circumferential flange 45 at its outer end is screwed into the end opening 42 of each baffle plate through the corresponding opening 43 in the end wall of the shell 13 to secure a water tight connection between the ends of the baffle plates and the shell. A location of the several nipples 40 44 of each set in vertical alignment upon the median plane of the heater is obtained by making the parts, as 46, 47, of each baffle 45 plate 41, which extend at opposite sides of the line of the end openings 42, of unequal 50 width. If desired, the baffle plates 41 may all be of like construction but adjacent plates will be so turned as to have the narrower part, as 46, extended in opposite directions from the line of the end openings 55 42.

Radiation from the exterior surface of the shell 10 will be useful in warming the room, as A (Fig. 1) in which the device is located. This radiation of heat may be supplemented by the use of a radiator, as 26, 60 through which water from the heater is circulated, as by means of the connecting pipes 24, 25. In event it is found that the room, as A, is sufficiently heated by radiation from 65 the exterior surface of the shell 10, the radi-

ator 26 may be located in an adjacent room, as B. The apparatus permits of a substantially complete utilization of the heat generated from burning gaseous fuel without permitting highly heated air or products of 70 combustion from the burner to mingle with the air in the room.

The distribution of the water in the water spaces 16 and 17 and in the chambers of the baffle plates 41 insures that the water will be 75 heated for service almost immediately upon lighting the burner 28 and that thereafter the desired temperature will be maintained even though the burner be turned quite low. Furthermore, the crescent shape of the baffle plates in cross section renders them 80 peculiarly efficient for heating the water which they contain. This arises from the fact that a greater depth of the layer of water within the chamber of each baffle plate is maintained adjacent the median line of the plate. A heater which is economical and efficient in operation and is of simple and inexpensive construction is accordingly provided. As shown, a gage glass 48 is provided. This 85 90 is desirably has its opposite ends connected with the water spaces 16 and 17 as through connecting pipes 49, 50, which extend through and are respectively connected with a side wall and the cover 11 of the shell 10. 95

I claim as my invention,—

1. In a heater, in combination, a chambered casing having hollow side, end and top and bottom walls, a vapor burner located within the interior chamber of the casing 100 and a plurality of chambered baffle plates of crescent shape in cross section located at different levels within the interior chamber of the casing above the burner with their concave surfaces downwardly facing, each baffle 105 plate being of less width than the said interior chamber of the casing and adjacent plates being located adjacent the opposite side wall of such chamber, all of the wall chambers of the casing and the chambers of the baffle plates being in communication for 110 containing water.

2. In a heater, in combination, a cast metal shell, a sheet metal shell of substantially the same shape but of smaller dimensions than the cast metal shell supported within the chamber of the cast metal shell with all of its walls separated from the corresponding walls of the cast metal shell to provide a continuous water space between the two, 120 tubular nipples, one for the introduction of a vapor burner and the other for receiving a flue, extending through the corresponding walls of both shells and making a water tight joint with each, chambered baffle plates 125 located within the chamber of the sheet metal shell and having their chambers opening into the space between the two shells through openings in the sheet metal shell and circulating pipes communicating with 130

the space between the two shells through openings in the said cast metal shell.

3. In a heater, in combination, a chambered casing oblong rectangular in plan section and having hollow side, end and top and bottom walls, the chambers of all of said walls being in communication for containing water, a vapor burner located within the interior chamber of the casing and a plurality of chambered baffle plates extending horizontally within the interior chamber of the casing from end to end of the same above the burner the chamber of each of the said baffle plates opening into the wall chambers 15 of the casing at the ends only.

4. In a heater, in combination, a chambered casing oblong rectangular in plan section and having hollow side, end and top walls, the chambers of all of said walls being 20 in communication for containing water, a vapor burner located within the interior chamber of the casing and a plurality of chambered baffle plates extending horizontally at different levels within the interior 25 chamber of the casing from end to end of the same above the burner, each of the said baffle plates being of less width than the interior chamber of the casing and adjacent plates being located adjacent the opposite 30 side walls of such chamber, the chamber of each of the said baffle plates opening into the wall chambers of the casing at the ends only.

5. In a heater in combination, a chambered casing oblong rectangular in plan section and having hollow side, end and top walls, the chambers of all of said walls being 35 in communication for containing water, a vapor burner located within the interior 40 chamber of the casing and a plurality of

chambered baffle plates of crescent shape in cross section extending horizontally at different levels within the interior chamber of the casing from end to end of the same above the burner and with their concave surfaces 45 downwardly facing, each of the said baffle plates being of less width than the interior chamber of the casing and adjacent plates being located adjacent the opposite side walls of such chamber, the chamber of each 50 of said baffle plates opening into the wall chambers of the casing at the ends only.

6. In a heater, in combination, a chambered casing oblong rectangular in plan section and having hollow side, end and top 55 walls, the chambers of all of said walls being in communication for containing water, a burner located within the interior chamber of the casing and a plurality of chambered baffle plates of crescent shape in cross section 60 extending horizontally at different levels within the interior chamber of the casing from end to end of the same above the burner and with their concave surfaces downwardly facing and a set of nipples in 65 vertical alinement upon the median plane of the casing at each end of the same, each nipple connecting the chamber of one of the baffle plates with the chamber of the corresponding end wall of the casing and the 70 parts of each baffle plate which are at opposite sides of the line of said nipples being of unequal width, adjacent baffle plates being arranged with the narrower of said parts at opposite sides of the median vertical plane 75 of the casing.
